UNITED STATES PATENT OFFICE.

HARRY T. WILLIAMS, OF INDIANAPOLIS, INDIANA.

VENEER-MACHINE.

No. 880,849.

Specification of Letters Patent.

Patented March 3, 1908.

Application filed February 14, 1907. Serial No. 357,271.

To all whom it may concern:

Be it known that I, HARRY T. WILLIAMS, a citizen of the United States, residing at Indianapolis, in the county of Marion and 5 State of Indiana, have invented certain new and useful Improvements in Veneer-Machines, and I do declare the following to be a full, clear, and exact description of the invention, reference being had to the accompanying drawings, and to the letters and 10 figures of reference marked thereon, which form a part of this specification.

This invention relates to machines for making veneering by sawing operations, and 15 the invention has reference more particularly to veneer saws and the mountings thereof.

The objects of the invention are to provide a veneer machine that will be adapted to produce relatively broad strips of veneering 20 by means of a circular saw having relatively small diameter; to provide a veneer machine of novel construction whereby in carrying out the above-mentioned object the saws may be quickly removed from the machine to be resharpened while replaced by a 25 sharpened saw so that the operations of the machine need not be delayed while re-sharpening the saws, thus avoiding lost time in the operations of the machine; a still further 30 object being to provide useful improvements in veneer saws and their mountings.

With the above-mentioned and minor objects in view, the invention consists in a veneer saw flange mounted removably on a 35 spindle or rotative shaft whereby to facilitate the changing of saws; and the invention consists further in the novel parts and the combinations and arrangements of parts as hereinafter particularly described and referred to in the following claims.

Referring to the drawings Figure 1 is a top plan of the improved machine partially broken away; Fig. 2, a transverse vertical sectional view approximately on the axis of 45 the veneer saw; Fig. 3, a front elevation of the improved saw and its support in which some of the saw blades are omitted from the saw flange; Fig. 4, a fragmentary side view of the saw spindle; Fig. 5, a fragmentary central sectional view of the saw flange; Fig. 6, a front elevation of the saw spindle 50 and its support; Fig. 7, a fragmentary front elevation of the saw flange; Fig. 8, a transverse sectional view of the saw flange

mounted on its spindle; Fig. 9, an elevation 55 of the mountings of the saw spindle; and, Fig. 10, a rear elevation of the saw flange partially broken away.

Similar reference characters in the different figures of the drawings designate corresponding elements or features of construction.

In practically carrying out the invention a suitable frame is provided comprising supports A and A' which are suitably mounted 60 either on a suitable foundation or on a mill floor, and they support a pair of journal bearings B and B' provided respectively with bearing caps C and C'. A spindle or shaft D is mounted rotatively in the bearings and 65 caps thereof and is provided with a collar D' for preventing longitudinal movement thereof. A pulley E is attached to the spindle and is driven by a belt F which may conveniently run through the mill floor to any 70 suitable driving means beneath. The front end of the shaft D that is near the bearing B has a tapering extremity D², rearward of which a collar G encircles the shaft D with a 75 tight fit thereon and is usually further secured by a key H to the shaft. The face of the collar is straight, the rear side thereof being beveled or somewhat like the frustum of the cone. A suitable number of threaded studs as I or I' are secured to the collar and 80 project forwardly beyond the straight face thereof so that they are arranged around the tapering portion D² of the spindle, the studs being provided for the double purpose of securing the saw flange to the spindle and its 85 collar, and for driving the flange and thereby the veneer saw. The collar G is provided also with a pair of screws J and J' that are mounted in the collar with their heads at the rear thereof so that the points of the screws 90 may be projected through and beyond the straight face of the collar to force the flange from the tapering end D² of the spindle, the screws being arranged at opposite sides of the 95 spindle in holes K and K' that are provided 100 in the collar to receive them. The studs I or I' are provided each with a nut L.

The saw flange M has a straight front face and beveled rear, being disk shaped as usual, and in the center thereof has a tapering hole 105 M' adapted to fit on the tapering portion D² of the spindle D so that the flange may always be depended upon to be tight on the

spindle and run true, the back of the flange having a recess N adapted to fit against the collar G, there being bolt holes O extending through the flange to receive the studs I or I', the outer ends of the bolt holes being greater in diameter than the inner portions of the holes, so that recesses O' are formed in the face of the flange to receive the nuts L. A suitable number of saw blades P or P' are 5 suitably secured to the peripheral portion of the saw flange and are removable so that they may be replaced by new ones when necessary. In the rear of the flange M is a threaded hole Q to receive a cap screw R whereby 10 to secure a hook S to the flange temporarily by means of a suitable shank S' with which the hook is provided so that a traveling hoist T may be connected with the hook for conveying the flange either way from or to 15 the saw spindle when changes are desired. 20 A pair of track rails U and U' are suitably supported in a plane below the plane of the spindle D, and a suitable carriage V is mounted so as to travel longitudinally on the rails 25 at the front of the saw, the carriage having a transversely adjustable head W mounted thereon that is provided with dogs X and X' for holding the "fitch" or slab Y from which to saw the veneering. The lowermost dog 30 X' is arranged in a plane but slightly above the horizontal plane of the spindle D so that the bottom of the fitch will pass above and relatively close to the axis of the spindle, thus requiring a saw of less diameter than 35 30 has usually been employed when the saw spindles have been provided with bearing supports at the front of the saw, such supports usually being devoid of bearing caps in order to avoid obstructing the path of the 40 fitch, but in any case preventing the fitch from passing near the axis of the saw, which disadvantage as will be apparent is overcome in the present invention. 45 In practical use the flange M is secured to the spindle D and its collar G as hereinbefore described, and the hook S and screw bolt R are to be detached from the flange and the machine may then be operated in the usual manner, and when the saw blades or seg- 50 ments P or P' become dull the machine may be stopped, the hook S applied to the flange M then the screws J and J' may be turned to dislodge the flange from the spindle after which the flange may be drawn off of the 55 studs I or I', the nuts L having been previously removed as will be understood, and by means of the traveling conveyer T the flange may be transferred to a suitable point in the mill and deposited, and then by means 60 of the conveyer another flange, the saws of which have been previously sharpened may be instantly conveyed and connected to the spindle and the flange G in the manner which will be understood from the foregoing de- 65 scription, and while using the sharpened saw

the other one may be resharpened so as to be ready for the next change that may be required.

Having thus described the invention, what is claimed as new is—

1. A veneer machine including a saw spindle, a saw-flange securely mounted removably on the spindle, saw blades secured to the flange, a collar secured to the spindle, and screws threaded into the rear of the collar and projectable against the flange to force the same from the spindle. 70 75

2. A veneer machine including a saw spindle, a collar secured to the spindle, a plurality of threaded studs secured permanently to the collar and projecting beyond a face thereof, a saw flange mounted removably on the spindle and having holes receiving the studs, and nuts on the studs in engagement with the flange. 80 85

3. A veneer machine including a saw spindle with a tapering end portion, a collar secured permanently to the spindle with the straight front face thereof at the larger part of the end portion, the opposite or rear face 90 of the collar being beveled, a plurality of threaded studs secured permanently to the collar and projecting beyond the straight face thereof, a saw flange mounted on the end portion of the spindle and against the front 95 face of the flange removably and having holes receiving the studs, the side of the flange that is against the collar being beveled from the collar outwardly and the other or front side being straight, said flange being 100 recessed in the straight face thereof about the holes, and nuts on the studs seated in the recesses against the flange. 105

4. A veneer machine including a rotative spindle having a collar secured thereto, the 105 spindle extending beyond the collar and having a tapering extremity, a saw flange mounted removably on the tapering extremity of the spindle and provided with a detachable carrying device, a plurality of screws securing the flange to the collar detachably, a pair of screws mounted in the collar to be projected against the flange, and saw blades secured to the flange. 110

5. A veneer machine including a saw 115 spindle having a collar thereon, a saw flange joined detachably to the spindle and the collar and having a hole therein to receive a carrying device, a plurality of screws securing the flange to the collar and the spindle, 120 and saw blades secured to the flange, said hole being between the saw blades and the middle portion of the flange.

6. A veneer machine including a rotative saw spindle having a collar secured permanently thereto, the spindle extending beyond the collar and having a tapering extremity, a saw flange mounted removably on the tapering extremity of the spindle, a plurality of screws securing the flange to the collar 125 130

and the tapering extremity of the spindle, a pair of screws mounted in the collar to be projected against the flange, and saw blades secured to the flange.

5 7. The combination of a saw spindle and a collar thereon, a saw flange mounted on the spindle removably and having a hole therein to receive a carrying device, saw blades secured to the flange, and securing screws enclosing the flange and the collar, with a de-

vice insertible into the hole in the flange for carrying the flange and the saw blades thereon away from or to the spindle.

In testimony whereof, I affix my signature in presence of two witnesses.

HARRY T. WILLIAMS.
